COAXIAL VARIABLE ATTENUATOR SWITCH

Dehman E. Rowe, Washington, D. C., assignor, by
mesne assignments, to the United States of
America as represented by the Secretary of the
Navy

Application August 30, 1945, Serial No. 613,511

3 Claims. (Cl. 178—44)

1

My present invention relates to the general problem of controlling the intensity of and the switching of guided electromagnetic energy, and more particularly to the provision of a combined variable attenuator and switch in a coaxial transmission line.

Heretofore, it has been necessary when seeking to control the intensity of signals being carried by a coaxial line or to switch those signals on or off, to use devices external to the coaxial line. As a consequence, it has further been necessary to use impedance matching devices between such attenuation or switching means. These devices introduce complexities involving relatively great weight and expense and difficulties in manufacture in coaxial line transmission systems. Systems involving the use of variable length stubs have been used and these systems too are complex and expensive to manufacture.

In my present invention, I provide a simple mechanism for varying the intensity of the signal in a coaxial line, and for switching that signal on and off. My invention makes use of the fact that the outer cylindrical conductor of the coaxial line is usually of too small a diameter to carry waves of energy at the operative frequency in any mode for a cylindrical wave guide. In my present invention, I disclose hereinbelow a novel manner of converting a section of coaxial line to a section of cylindrical wave guide of variable length, thereby affording a means of gradually increasing the attenuation of the wave energy therein being carried and with increasing length of the wave guide section of switching off of that signal completely.

It is an object of my invention to provide in one section of coaxial wave guide, a combined variable attenuator and switch for the energy being carried therein.

It is a further object of my invention to provide such a combined variable attenuator and switch that will be light in weight, simple to manufacture and simple to adjust and operate.

It is a further object of my invention to provide such an attenuator and switch that will control positively the switching on and off and intensity of the energy in said wave guide.

Other objects and features of my present invention will become apparent upon a careful consideration of the following detailed description when taken together with the accompanying drawings, the figures of which illustrate a typical embodiment of the invention.

Fig. 1 illustrates in cross section a coaxial line variable attenuator and switch constructed in accordance with my invention; and

2

Fig. 2 illustrates in electrical scheme a coaxial line having the inner conductor foreshortened to convert one end of the line to a cylindrical wave guide.

In Fig. 1, a first coaxial line 1 having an outer conductor 1' is joined at right angles to a second coaxial line 2 in a usual and common fashion. The second coaxial line 2 is connected to the first coaxial line 1 a short distance from a closed end 10 of said first coaxial line 1. An end closure 3 having a circular opening in its center is furnished in the closed end of the first coaxial line 1. An inner conductor in the first coaxial line 1 is made up of two sections 4 and 4' arranged collinearly on the longitudinal axis of the outer conductor 1'. The first section 4 of the inner conductor is fixedly mounted concentrically within the first coaxial conductor 1' and supported by an insulating bead 5 which may be made of polystrene or like insulating substance. The second section 4' of the inner conductor of the first coaxial line 1 is hollow and is fixedly positioned in the closed end of the first coaxial line 1 a fixed distance from the thereunto directed end 15 of the first inner conductor section 4. This second section 4' is inserted in the aforementioned circular opening in the end closure 3 and projects a relatively short distance into the first coaxial line 1. The inner conductor 1' of the second coaxial line is connected to the second section 4' of the center conductor of the first coaxial line 1. The mutually directed ends 8 and 9, respectively, of the two sections 4 and 4' of the inner conductor of the first coaxial line 1 are hollow and have spring-like fingers or contactors made by slotting those ends. A cylindrical rod-shaped member 6 is slidably inserted in the second inner conductor section 4' in the closed end of the first coaxial line 1, and is movable in either direction along the longitudinal axis thereof. The spring-finger contactors in the end 8 of the second inner conductor section 4' make firm electrical but slidable contact with this cylindrical rod-shaped member 6. A mechanical stop 10 is fastened to the outer end of the rod 6 to prevent the rod 6 from falling into the coaxial line 1 when it is pushed in and to provide a handle thereon. The inwardly-directed end of the rod 6 is pointed to form an electrical probe 11. This electrical probe 11 is adapted to fit into the spring-finger contactors in the thereunto directed end 9 of the first inner conductor section 4 and establish slidable electrical contact therewith when the rod 6 is pushed toward the first inner conductor section 4. The rod 6 may be pushed into the coaxial line 1 far

enough for the probe 11 to be inserted completely in the spring-fingered end 9 of the first section 4 of the inner conductor thereof. The rod 6 may also be pulled out of the coaxial line 1 far enough to establish a substantial gap d between the probe 11 and the spring-fingered end 9 of the first inner conductor section 4 with which the probe 11 cooperates. The width of this aforementioned gap d is therefore variable. The mutually directed ends 8 and 9 of the two sections 4' and 4, respectively, of the inner conductor of the coaxial line 1 are as aforementioned separated by a fixed distance. The rod 6 is adapted electrically and mechanically to vary this aforementioned fixed distance.

Electromagnetic energy may be introduced into or taken from the apparatus at either end. In the hereinafter following discussion, it will be assumed that such energy is being introduced at the open end of the first coaxial line 1 and taken from the apparatus at the open end of the second coaxial line 2.

The apparatus of Fig. 1 works in a manner that can be best explained with reference to Fig. 2. Fig. 2 illustrates, a coaxial line 15 which has a center conductor 16 fore-shortened so that one end, here the right-hand end 15' of the coaxial line 15, is in fact a cylindrical wave guide. Dotted lines 17 illustrate lines of force of the electric field extending from the center conductor 16 to the outer cylindrical conductor 19 of the coaxial line 15. The diameter 18 of the outer cylindrical conductor 19 is of a relatively too small size for wave guides but of a usual and ordinary size for coaxial lines. Thus the cylindrical wave guide portion 15' is not adapted to carry electromagnetic energy in any wave guide mode at the frequency of operation, as will be hereinbelow explained.

In order that the wave guide end 15' of the apparatus of Fig. 2 may function as a wave guide, the diameter 18 thereof must be at least 0.57 times as great as the wave length in free space of energy at the operative frequency. However, the outer conductor 19 of a coaxial line as illustrated in Fig. 2 is usually of much smaller diameter than 0.57 times the wave length of energy at the operative frequency. As a result, the electric field 17 beyond the inwardly terminated end of the inner conductor 16 will possess a certain amount of energy, and at a frequency below cut-off frequency the impedance to the flow of this energy in the wave guide section 15' will be exceedingly large, so that the coaxial line may be considered as opened in the electrical sense as well as in the mechanical. Of course, should the frequency of operation increase, this impedance will decrease and displacement current will take place in the hollow cylinder 15' in increasing quantity. In this manner the hollow cylindrical portion 15' would be converted to an operative wave guide. However as aforementioned, the diameter 18 is not sufficiently great to permit such action, and the hollow cylindrical wave guide section 15' may be said therefore to be a cylindrical wave guide operating at a frequency below cut-off frequency for that wave guide. In the cylindrical wave guide 15' operating below the cut-off frequency, waves are attenuated even though there is no loss of energy. This means that the energy merely fluctuates between the source namely the coaxial pair 19 and 16 and the tube or pipe 15'. Above the cut-off frequency some energy would pass into the tube 15' and travel along that tube. As hereinabove men-

tioned, the diameter 18 would have to be at least 0.57 times the free space wave length of energy at the operative frequency before waves in even the lowest mode for cylindrical wave guides would be carried by the hollow pipe 15'.

In the apparatus of Fig. 1, the region in the neighborhood of the end 9 of the first inner conductor section 4 resembles the region in the neighborhood of the inwardly directed end of the inner conductor 16 of the apparatus of Fig. 2. That is, the hollow pipe section of length d is in effect a cylindrical wave guide when the probe 11 is pulled back from the thereunto directed end 9 of the first conductor section 4. 15 Lines of electric force similar to the lines 17 of Fig. 2 exist in the neighborhood of the therewith cooperating end 9 as the probe 11 is separated from the said end 9. When the probe 11 is within the end 9 of the first inner conductor section 4, positive electrical contact is established for the entire inner conductor comprising sections 4 and 4' and the rod 6. As the probe 11 is pulled out of the end 9, the aforementioned lines of electrical force establish electrical contact between the probe 11 and the end 9. The electrical contact established by the aforementioned lines of force diminishes in strength as the probe 11 is pulled further and further away from the end 9 of the first inner conductor section 4. Thus 20 there is attenuation of the energy passing through the coaxial line 1 since the diminishing in electrical contact is tantamount to an increase in impedance to the flow of energy in the coaxial line 1. When the distance d separating the probe 11 and the end 9 becomes sufficiently great, effective contact between the probe 11 and the end 9 becomes substantially broken, thereupon causing a switching action which interrupts the flow of energy in the coaxial line 1. At this point, as in the apparatus of Fig. 2 a section of the outer conductor 1' of length d between the probe 11 and the end 9 becomes a cylindrical wave guide which is of too small a diameter to carry energy in any mode for cylindrical wave guides, and therefore, presents a large impedance to signals flowing in the coaxial line 1. As aforementioned in connection with the discussion of Fig. 2, the coaxial pair comprising the outer conductor 1' and the first inner conductor section 4 is practically opened in the electrical sense as well as in the mechanical sense.

Thus it can be seen that my invention provides a variable attenuator and switch for a coaxial line. Although I have shown and described only a certain specific embodiment of my invention, I am fully aware of the many modifications possible thereof. Therefore my invention is not to be limited except insofar as is necessitated by the prior art and the spirit of the appended claims.

I claim:

1. In a coaxial transmission line an inner conductor comprising first and second hollow cylindrical members coaxially mounted a fixed distance apart and a third cylindrical member telescopically mounted within said first member in slidable electrical contact therewith, means for sliding said third member within said first member in either direction parallel to the longitudinal axis thereof, a tapered electrical probe in the end of said third member directed toward the mutually directed end of said second member, and means in said last mentioned mutually directed end for establishing slidable electrical

contact with said third member when said probe is inserted therein.

2. A variable attenuator and switch for a coaxial transmission line comprising an outer cylindrical conductor of a diameter smaller than that required to carry energy at the operative frequency in any mode for a cylindrical wave guide, an inner conductor having first and second hollow cylindrical members fixedly mounted in said outer conductor a fixed distance apart on the longitudinal axis thereof and a third cylindrical member telescopically mounted within said first member in slidable electrical contact therewith, said third member being of sufficient length to touch both said first and said second members simultaneously and having a tapered electrical probe in its end directed toward said second member, means in said second member in its end facing toward said first member for cooperating with said probe to establish slidable electrical contact therewith when said probe is inserted therein, and means for sliding said third member axially within said first member.

3. A variable attenuator and switch for a coaxial transmission line comprising a first coaxial line having a closed end, a second coaxial line electrically coupled to said first line near said closed end, the inner conductor of said first coaxial line having first and second hollow cylindrical members spaced a fixed distance apart, 30

said first member being mounted in said closed end and extending therethrough and in electrical contact with the inner conductor of said second coaxial line, a third cylindrical member slidably mounted within said first member in electrical contact therewith and extending outwardly through said closed end and inwardly into said first coaxial line toward said second member, means in the mutually directed ends of said second and third members for establishing slidable electrical contact therebetween, and means comprising the outwardly extending portion of said third member for moving said third member axially with respect to said first coaxial line.
